[57] CLAIM

The ornamental design for a padlock, as shown and described.

DESCRIPTION

FIG. 1 is a front elevational view of a padlock showing our new design.

FIG. 2 is a back elevational view thereof.

FIG. 3 is a right side elevational view thereof.

FIG. 4 is a top elevational view thereof.

FIG. 5 is a view similar to FIG. 4 but having parts of the housing and dial broken away.

FIG. 6 is a frontal perspective view of our padlock taken from above and to one side.

FIG.1
